(57) **CLAIM**

The ornamental design for a reach-through lid for bucket style cooler, as shown and described.

DESCRIPTION

FIG. 1 is a top perspective view of a reach-through lid for bucket style cooler showing my new design, wherein a bucket style cooler and refreshments are shown in dashed line to illustrate the intended use environment therefor and form no part of the claimed design;

FIG. 2 is a top perspective view comparable to FIG. 1, except with the environment matter removed from view;

FIG. 3 is a top plan view thereof, wherein the bottom plan view forms no part of the claimed design;

FIG. 4 is a side edge elevational view, wherein all three other sides are identical thereto;

FIG. 5 is an section view taken along line V-V in FIG. 3;

FIG. 6 is an enlarged-scale side elevational view, partly in section, of detail VI-VI in FIG. 5; and,

FIG. 7 is an enlarged-scale side elevational view, partly in section and with central portions broken away, of detail VII-VII in FIG. 5.

The broken lines form no part of the claimed design.
